Primary Examiner — Melody N Brown

CLAIM

The ornamental design for a motor vehicle body, toy vehicle body replica and/or other replica, as shown and described.

DESCRIPTION

FIG. 1 is a front and left side perspective view of a motor vehicle body, toy vehicle body replica and/or other replica showing my new design;

FIG. 2 is a rear and left side perspective view thereof;

FIG. 3 is a front elevation view thereof;

FIG. 4 is a left side elevation view thereof;

FIG. 5 is a right side elevation view thereof;

FIG. 6 is a rear elevation view thereof; and,

FIG. 7 is a top plan view thereof.

The broken lines in the drawings depict portions of the motor vehicle body, toy vehicle body replica and/or other replica that form no part of the claimed design.

1 Claim, 7 Drawing Sheets
